UNITED STATES PATENT OFFICE.

CHARLES J. KLEIN, OF MILWAUKEE, WISCONSIN.

CASING FOR LAMP-SOCKETS, PENDANT-SWITCHES, AND THE LIKE.

1,151,799.

Specification of Letters Patent. Patented Aug. 31, 1915.

Application filed March 17, 1913. Serial No. 754,806.

To all whom it may concern:

Be it known that I, CHARLES J. KLEIN, a citizen of the United States, residing at Milwaukee, in the county of Milwaukee and State of Wisconsin, have invented new and useful Improvements in Casings for Lamp-Sockets, Pendant-Switches, and the like, of which the following is a full, clear, concise, and exact description, reference being had 10 to the accompanying drawing, forming a part of this specification.

My invention relates to casings for lamp sockets, pendant switches and the like.

It has among its objects to provide an improved and simplified two-part casing wherein when the parts of the same are brought together they are locked against relative rotation and longitudinal separation but are at the same time readily separable longitudinally when desired.

Other objects and advantages of my improvement will hereinafter appear.

In order that my invention may be clearly and fully disclosed, I have illustrated several embodiments of the same in the accompanying drawings.

Figure 1 is a side elevation of an assembled casing; Fig. 2 is a partial longitudinal sectional view of the same with a cap positioned above the shell; Fig. 3 is a sectional view of the cap on line 3—3 of Fig. 2; Fig. 4 is a detail of the catch on the shell; Fig. 5 is a partial sectional view showing the cap in position; Fig. 6 is a sectional view on line 35 6—6 of Fig. 7 showing the modified construction; Fig. 7 is a side elevation of the construction shown in Fig. 6; Fig. 8 is a detail view of a modified form of catch; Fig. 9 is a partial sectional view of the construction shown in Fig. 8; Fig. 10 is a bottom plan view of a modified form of cap; Fig. 11 is a detail view of a shell adapted to be used with the construction shown in Fig. 10. Fig. 12 is a side elevation of a modified form 45 of shell adapted to use with a construction shown in Fig. 10; Fig. 13 is a sectional view on line 13—13 of Fig. 12.

The casing shown comprises a cap 1 and a shell 2 provided with engaging members, 50 hereinafter described, for locking the parts together.

In the construction shown in Figs. 1 to 5, the rim of the cap 1 is expanded angularly as shown at 3 and upon its edge an inwardly 55 extending flange 4 is provided adapted to co-operate with catches on the shell 2, herein-

after described, to lock the parts together. This flange is protruded substantially at right angles to the axis of the cap and is provided with a plurality of substantially 60 rectangular shaped notches or slots 5 disposed through its edge in a regular spaced relation. The shell 2 is substantially cylindrical and resilient at its upper end, being provided with one or more longitudinally 65 extending slots 6 to permit the side walls 7 of the same to be compressed. These side walls carry one or more suitable catches 8 adapted to be received in the slots 5 in the flange 4. In the drawings I have shown the 70 catches 8 to be formed integral with the member 2 and punched out therefrom so as to extend substantially at right angles to the periphery thereof. In a preferred form the upper edge of each of these catches 8 is tapered downward as shown at 9 in Fig. 4 and is provided with a horizontally disposed edge or ledge 10 at the end of the tapered portion and at right angles to the elongated body portion of the catch. To attach the members 1 and 2, the catches 8 in the casing 2 are made to register with certain of the slots 5 in the cap flange 4. Upon a longitudinal movement of either the cap or shell toward the other and a compression 75 of the resilient portion of the member 2, the tapered edges 9 on the catches 8 clear the end walls of the slots 5 and the catches move through these slots until the horizontal portions 10 of the catches come opposite the 80 inner horizontal surface of the flange 4. The pressure upon the resilient end of the member 2 being then relieved, the horizontal portions 10 spring outward so that they rest upon the horizontal portion of the flange 85 90 95 100 adjacent the inner end of the slots 5 and immediately back of the same, thus providing a positive lock for preventing longitudinal separation of the members 1 and 2. At the same time the vertically extending body portion of the catches 8 beneath the horizontally disposed ledges 10 are received in the slots 5 and engage the side walls of the same to positively lock the parts against relative rotation. When it is desired to separate the 105 members 1 and 2, however, by simply pressing the resilient upper end of the member 2 at points beneath the catches, the catches are moved toward each other to cause the ledges 10 to again register with the slots 5, 110 whereupon the parts may be readily separated by a longitudinal movement.

In the construction shown in Figs. 6 and 7 I have illustrated the shell 2 as provided with laterally extending curved ears 11 having their edges tapered away from the slots 5 in the end of the shell. There are also provided in the shell one or more laterally extending struck-out portions 12 spaced from the ears 11. As shown in Fig. 7, the ears 11 are preferably provided upon the bottom edge of a substantially rectangular cut-away portion 13 provided at one side of the slots in the member 2 and the projections 12 are provided with rounded upper edges 14 instead of a tapered portion. This construction is adapted to use with a cap having a flange of the same construction as shown in Fig. 3. When it is desired to attach the member 2 to the cap, the lips 11 are forced inward and the projections or struck-out portions 12 are brought in registry with the slots 5. The members 1 and 2 are then brought together causing the projection 12 to enter in the slots 5 and by their engagement with the side walls of the same act as a positive means for preventing relative rotation. Due to the resiliency of the shell when the compression upon the end of the same is removed, the lips 11 spring outward and their under surfaces rest upon the upper surface of the horizontal flange 4 and thus provide a positive lock against accidental longitudinal separation.

In Figs. 8 and 9 is shown a further modified construction which is likewise adapted to be used with a cap of the construction shown in Fig. 3. In this construction the member 2 is provided with a plurality of vertically extending struck-out portions 15, tapering toward the wall of the member 2 at their upper ends as shown at 16, and of greater width at their lower end where they are provided with a horizontally disposed edge 17. These catches 15 are disposed parallel to each other in pairs on one or both sides of the resilient end of the member 2 and are preferably struck-up from the metal thereof on opposite sides of a substantially rectangular shaped opening 18 formed therein. Coöoperating with these catches 15 is another catch carried by a member inclosed within the member 2. In a preferred form this catch 19 is formed of a single sheet of metal having its inner end embedded in the insulating base 20 of a switch mechanism or other device. The outer end of this catch 19 is provided with a notch 21 in its lower edge adapted to fit over the wall of the member 2 between the catches 15 and is likewise provided with an elongated downwardly extending portion 22 and a cut-away portion 23 above the same. It is to be noted that the elongated portion 22 of the catch 19 extends below the horizontal edges 17 of the catches 15. To attach the member 2 to a cap of the construction shown in Fig. 3, the catches 19

are brought into registry with the slots 5 therein and the resilient sides of the member 2 are compressed at points beneath the catches 15. This compression forces the catches 15 inward enabling the tapered edges 78 of the same to pass the portions of the flange 4 between the slots 5. When the pressure upon the sides of the member 2 is removed, due to the resiliency of the end of this member, the catches 15 immediately spring outward over the flange 4 and their horizontally disposed portions 17 rest upon the horizontal upper surfaces of the flange, thus providing positive means for locking the parts against longitudinal separation. At 80 the same time the lower end of the member 22 is still in the slot 5 and in engagement with the side walls of the same, thus providing a positive means for locking the parts against relative rotation. Obviously a plurality of catches of this form may be provided upon opposite sides of the member 2 in the same manner as shown in connection with the other forms illustrated.

In Figs. 10 and 11 I have illustrated a further modified form of my invention. In this construction the member 1 is provided with slots in its flange disposed in the same manner as the slots shown in Fig. 3 but the slots are wider. The catch adapted to co-operate with these slots is shown in detail in Fig. 11 and comprises a resilient member 24 integral with the casing member 2 and extending longitudinally thereof, being punched out therefrom along parallel longitudinally disposed slits 25. Near its upper end this resilient member or tongue 24 is provided with a horizontally disposed portion or ledge 26 extending substantially at right angles to its body portion and above 105 this ledge 26 the upper end of the member 24 is preferably bent inward at an angle of 45 degrees as shown at 27 to form a catch. To lock the members 1 and 2 together when this form of catch is used, the upper ends 27 110 of the catches 24 are brought in registry with the slots 5 of the flange 4. Upon continued longitudinal movement of the parts toward each other, the portion 27 of the resilient tongue or catch 24 engages the end 115 wall of the slot and yields inwardly until the ledge 26 is opposite the horizontal surface of the flange at the back of the slot. Due to their resilient construction the catches 24 then spring outward and the horizontal 120 ledge 26 on the catches rests firmly upon the horizontal surface of the flange at the ends of the slots and thus establishes a positive means for preventing accidental longitudinal separation of the parts. At the same time the vertically extending edges of the member 24 engage the side walls of the slots 5 and thus provide a positive lock preventing relative rotation of the parts.

In Figs. 12 and 13 I have illustrated an- 125

other modified construction adapted to be used in connection with a cap of the construction shown in Fig. 10. In this construction the upper resilient end of the member 2 is provided with one or more ears or lugs 28 of rounded conformation, which are struck-out above horizontal slits 29, in a well-known manner. These portions 28 are located between a pair of vertically extending struck-out portions 30 punched out from between vertically extending parallel slits 31 in the end of the member 2 and are formed integral therewith. In this construction when the pressure is removed from the resilient end of the member 2 the cut edges of the projections 28 snap over that portion of the flange 4 at the end of the slots 5 to positively prevent longitudinal separation of the parts while the edges of the catches 30 engage the side walls of the slots to positively prevent a relative rotary movement of the parts.

While I have shown certain preferred forms of my improved device, it will be understood that various other modifications thereof may be made without departing from the scope or spirit of the invention, as claimed.

What I claim as new and desire to secure by Letters Patent is:

1. In casings for incandescent lamp sockets, in combination, a cap having an inwardly extending flange provided with a series of radial notches therein, a resilient shell having one end adapted to enter said cap, and means carried by said shell adapted to engage with the face of said flange and the sides of said notches to lock said cap and shell against axial separation and relative rotary movement.

2. In casings for incandescent lamp sockets, in combination, a cap having an inwardly extending flange provided with a series of radial notches therein, and a resilient shell having a plurality of outwardly pressed projections at one end to enter said cap, the edges of said projections being adapted to engage with the face of said flange and the faces of said projections being adapted to engage with the edges of said flange to lock said cap and shell against axial separation and relative rotary movement.

3. In casings for incandescent lamp sockets, in combination, a cap having an inwardly extending flange provided with a series of radially disposed notches therein, and a resilient shell having a plurality of outwardly extending projections forming shoulders adjacent one end adapted to enter said cap, said shoulders being adapted to enter said notches to engage said flange adjacent its outer periphery and in alinement with said notches.

4. In casings for incandescent lamp sockets,

in combination, a cap having an inwardly extending flange provided with a series of radially disposed notches therein, and a resilient shell having a plurality of outwardly extending projections adjacent one end adapted to enter said cap under compression, said projections being adapted to pass through said notches when said shell is under compression and to engage the face of said flange when the compression is relieved to lock said cap and shell against separation.

5. In casings for incandescent lamp sockets, in combination, a cap having an inwardly extending flat flange provided with a series of radially disposed notches therein, a resilient shell having one end adapted to enter said cap under compression, and means carried by said shell adapted to pass through said notches when said shell is under compression and to engage with the face of said flange and the sides of said notches when the compression is relieved to lock said shell and cap against axial separation and relative rotary movement.

6. In casings for incandescent lamp sockets, in combination, a cap having an inwardly extending flat flange provided with a series of radial notches therein and a resilient shell having a plurality of projections formed by cutting the metal vertically to the upper edge thereof and pressing a portion outwardly, said projections being adapted to engage with the face of said flange and the sides of said notches to lock said cap and shell against axial separation and relative rotary movement.

7. In casings for incandescent lamp sockets, in combination, a cap having an inwardly extending flange provided with a series of radially disposed notches therein and a resilient shell having a plurality of projections narrower than said notches adjacent one end adapted to enter said cap under compression, the edges of said projections being adapted to engage with the face of said flange when the compression is relieved, to lock said cap and shell against axial separation.

8. In casings for incandescent lamp sockets, in combination, a cap having an inwardly extending flange provided with a radially disposed notch therein and a resilient shell carrying an outwardly extending projection adjacent one end, said shell being adapted to enter said cap only when said projection registers with said notch, said projection being adapted to engage with said flange to lock said cap and shell against axial separation.

9. In combination, a cap having an in-turned marginal portion with a radial recess therein, and a shell adapted to enter said cap and provided with a projection adapted to engage the upper face of said in-turned

portion in radial alinement with said recess, said projection having a portion of reduced size to enter said recess.

10. In casings for incandescent lamp sockets, in combination, a cap having an in-turned marginal portion provided with a radial notch, a resilient shell having one end adapted to enter said cap, and a projection associated with said shell comprising vertical and horizontal shoulders adapted to engage with the face of said inturned por-

tion and the sides of said notches to lock said cap and shell against relative rotation and axial separation.

In witness whereof, I have hereunto subscribed my name in the presence of two witnesses. 15

CHARLES J. KLEIN.
